CLAIM

The ornamental design for a display portion of a hand held scanning tool, as shown and described.

DESCRIPTION

FIG. 1 is a perspective view of a display portion of a hand held scanning tool showing my new design; and,

FIG. 2 is a front view thereof, on an enlarged scale.

The broken lines shown in FIGS. 1-2 are environmental

only and form no part of the claimed design.

1 Claim, 2 Drawing Sheets

FIG. 2
